UNITED STATES PATENT OFFICE.

FRANK WILCOMBE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

TRUNNION-MOUNTED ELEMENT FOR KNITTING-MACHINES.

1,244,269.

Specification of Letters Patent.

Patented Oct. 23, 1917.

Application filed July 1, 1916. Serial No. 107,107.

To all whom it may concern:

Be it known that I, FRANK WILCOMBE, a citizen of the United States, and resident of Norristown, Pennsylvania, have invented 5 certain new and useful Improvements in Trunnion-Mounted Elements for Knitting-Machines, of which the following is a specification.

The invention relates to knitting machine 10 elements or implements that have a rocking motion, such for instance, as pivoted web holders, and it concerns particularly the pivotal bearing and journal for said elements.

The invention consists in the features and 15 combination and arrangement of parts hereinafter described and particularly pointed out in the claims.

In the accompanying drawings;

Figure 1 is a sectional view of part of a 20 knitting machine embodying the invention.

Fig. 2 is a side view of part of the bed which supports the rocking elements, with 25 said elements in place.

Fig. 3 is a plan view showing details.

Fig. 4 is a view of one of the elements 30 with its trunnion.

Fig. 5 shows a detail.

Heretofore it generally has been the practice in order to make a pivotal mounting to 35 string the elements or implements on a wire or to notch them and mount them on the wire, the elements being spaced apart by the walls of a slotted bed or carrier.

In carrying out my invention, each implement, as for instance a web holder, is 40 furnished with its own trunnions, such as shown at 4, the web holder itself being indicated at 5.

The bearing to receive these journals or 45 trunnions is formed by slotting the bed, say radially, at 6, and forming a circumferential groove, say at 7, in the tops of the walls left standing, this slotting and grooving providing guiding walls and notches forming

50 bearings to receive the trunnions. The elements or implements are simply dropped into these slots with their trunnions seated in the notches and the pivotal connection is thus effected. To hold the elements in place

55 I provide guard means and while this may vary in arrangement and construction, in the particular form shown, it consists of a guard plate 9 resting upon the upper edges

10 of the heads of the web holders, which edges are struck concentric with the trunnion so that in all positions of the web holder or other implement it will be held 55 with its trunnion properly seated in the bearing.

This guard simply rests by gravity on the 60 web holders. It is held in position against vertical or lateral displacement by any suitable means, for instance, by the adjacent wall 11 of the upper structure. The guard 65 may be held in place in various ways but in the particular construction shown, a plate 12' is removably seated in place on the cap or cover 12, said plate having brackets 13, 14, which support the arm holding the presser wheel 15. The plate 12' closely 70 overlies the guard and holds it down in place resting on the upper edges of the web holders. Any one or all of the pivoted implements may be removed by lifting off the plate 12' and taking off the guard, whereupon access is had to any web holder so that 75 it may be lifted out of place or be replaced.

I do not restrict myself to the particular kind of implement or element shown herein and the disposition of the open bearing sockets 80 may be changed to suit the character and disposition of the element having the trunnions.

The trunnions, particularly in the case of circular machines of small diameter, are 85 formed tapered to suit the curvature of the bearing notches which, as above pointed out, are formed by grooving the bearing wall circumferentially and preferably before the radial slots are formed in said wall. The 90 trunnions are swaged into connection with the implements, thus providing fillets at the sides of the implements about the trunnions which serve to center the implements in the slots which necessarily are cut somewhat 95 wider than the implements.

In renewing a damaged web holder it is simply necessary to remove it from its slot and replace it with another one. Each implement or web holder carries its own journal and in case of wear or a defect developing in the trunnion it will be necessary to 100 replace only this one implement, all the others being left undisturbed.

In supplying the implements with their 105 trunnions a hole in the implement receives a

small section of round wire, which is upset in the hole to make it fit tightly, shoulders being pressed upon the wire bearing on opposite faces of the implement or the trunnions can be brazed in place.

Certain features shown herein and not claimed are made the subject of another application.

What I claim is:—

- 10 1. In combination in a knitting machine, like implements in series having rocking motion, a carrier having guiding walls for the implements and grooved transversely of the guiding walls, said implements having trunnions individual and fixed thereto bearing in the grooves, and having surfaces at their free ends concentric with the trunnions and holding means bearing on said surfaces to retain the implement with the trunnion in the bearings.
- 15 2. In combination in a knitting machine, an implement having rocking motion, with trunnions individual thereto, and fixed thereon, a bearing for the trunnions having an open upper side for the removal of the implements with their trunnions, said implements having upper surfaces concentric with the trunnions and removable guard means engaging said concentric surfaces to retain the implements with the trunnions in their bearing.
- 20 3. In combination in a circular knitting machine for making fabric of small diameter, independently operating needles, a series of independently operating implements to coöperate with the needles and each having rocking movement, a ring-shaped carrier having radial guiding walls for the implements and grooved circumferentially in respect to the ring-shaped carrier, said independently operable implements having trunnions tapered outwardly from the sides of the implements to conform substantially to the steep arc of the circumferential groove, said trunnions being fixed to the implements to constitute one unit therewith and seated removably in the curved grooves, substantially as described.
- 25 4. In combination in a circular knitting machine for making fabric of smaller diameter, independently operating needles, a series of independently operating implements to coöperate with the needles and each having rocking movement, a ring-shaped carrier having radial guiding walls for the implements and grooved circumferentially in respect to the ring-shaped carrier, said independently operable implements having trunnions tapered outwardly from the sides of the implements to conform substantially to the steep arc of the circumferential groove, said trunnions being fixed to the implements to constitute one unit therewith and seated removably in the curved grooves, substantially as described.
- 30 5. In combination in a circular knitting machine, needles, pivoted web holders having individual trunnions seated in bearings and removable upwardly and individually, said web holders having upper portions with edges concentric with the pivots, and a guard plate resting on the concentric edges for holding the web holders in their bearings, substantially as described.
- 35 6. In combination in a circular knitting machine, needles, web holders pivotally supported and having a fabric engaging nose, the upper edge of the web holder being concentric with the pivot thereof, said web holders being individually removable upwardly from their pivot bearings and means engaging the upper concentric edges of the web holders for holding them in their pivot bearings, substantially as described.
- 40 7. In combination in a circular knitting machine, needles, web holders pivotally supported and having a fabric engaging nose, the upper edge of the web holder being concentric with the pivot thereof, said web holders being individually removable upwardly from their pivot bearings and means engaging the upper concentric edges of the web holders for holding them in their pivot bearings, substantially as described.
- 45 8. In combination in a circular knitting machine, needles, pivoted web holders having individual trunnions seated in bearings and removable individually, said web holders having surfaces concentric with their pivots, and a guard plate resting on the concentric surfaces for holding the web holders in their bearings, and a cover for holding the guard plate in place, said cover and plate being removably mounted, substantially as described.
- 50 9. In combination in a circular knitting machine, needles, web holders pivotally supported and having a fabric engaging nose, the upper edge of the web holder being concentric with the pivot thereof, said web holders being individually removable upwardly from their pivot bearings and means engaging the upper concentric edges of the web holders for holding them in their pivot bearings, substantially as described.
- 55 10. In combination in a circular knitting machine, needles, pivoted web holders having individual trunnions seated in bearings and removable individually, said web holders having surfaces concentric with their pivots, and a guard plate resting on the concentric surfaces for holding the web holders in their bearings, and a cover for holding the guard plate in place, said cover and plate being removably mounted, substantially as described.
- 60 11. In combination in a knitting machine, needles, web holders individually pivotally mounted, and each having an upstanding portion and an arm extending radially outward, and with the pivot at the junction of said upstanding portion and radial arm, the
- 65 each trunnion having a fillet adjacent the

sides of the implements to center the implements between the radial guiding walls of the carrier, substantially as described.

5. In combination a series of like rocking knitting machine elements, each having trunnions fixed thereto, and having surfaces concentric with the trunnions, each element and its trunnions removable from the series as a unit, and guard means bearing against the concentric surfaces for holding the elements in place.

6. In combination in a knitting machine, like instruments in series having rocking motion, trunnions individual and fixed thereto, guard surfaces on said implements concentric with the trunnions, a detachable clamping device against which the concentric surfaces bear, a carrier having guiding side walls for spacing the implements and grooved transversely of the guiding walls for the reception of the trunnions.

7. In combination in a knitting machine, a slotted needle cylinder, implements each having trunnions individual and fixed thereto, and having free ends with concentric surfaces, said free ends being spaced and guided by the walls of the slots, and guard means bearing on the concentric surfaces for holding the implements in place.

8. In combination in a circular knitting machine, needles, pivoted web holders having individual trunnions seated in bearings and removable upwardly and individually, said web holders having upper portions with edges concentric with the pivots, and a guard plate resting on the concentric edges for holding the web holders in their bearings, substantially as described.

9. In combination in a circular knitting machine, needles, web holders pivotally supported and having a fabric engaging nose, the upper edge of the web holder being concentric with the pivot thereof, said web holders being individually removable upwardly from their pivot bearings and means engaging the upper concentric edges of the web holders for holding them in their pivot bearings, substantially as described.

10. In combination in a circular knitting machine, needles, pivoted web holders having individual trunnions seated in bearings and removable individually, said web holders having surfaces concentric with their pivots, and a guard plate resting on the concentric surfaces for holding the web holders in their bearings, and a cover for holding the guard plate in place, said cover and plate being removably mounted, substantially as described.

11. In combination in a knitting machine, needles, web holders individually pivotally mounted, and each having an upstanding portion and an arm extending radially outward, and with the pivot at the junction of said upstanding portion and radial arm, the

upstanding portion at its top having an inwardly extending head, with a fabric engaging throat at the inner end thereof, the upper edge of the head being concentric 5 with the pivot, cam means for operating the radially extending arm, and a plate overlying and engaging the upper concentric edge of the inwardly extending head to hold said web holder down in its pivot bearings, 10 substantially as described.

12. In combination in a circular knitting machine, a needle cylinder having radial slots in its top, a ring encircling the upper part of the cylinder and slotted radially at

its top, pivoted web holders mounted on 15 said ring below the top thereof, said web holders having an upper portion extending inwardly and guided by the slots in the ring and buried in the cylinder top, and having a fabric engaging throat above the cylinder verge, said web holders having outwardly extending arms and operating means therefor for imparting rocking movement to the web holder into and out of engagement with the fabric, substantially as de- 20 25 scribed.

In testimony whereof, I affix my signature.

FRANK WILCOMB.
